PHOTOSENSITIVE TUBE

William Maurice Patterson, Fairland, Ind., assignor to Westinghouse Electric & Manufacturing Company, East Pittsburgh, Pa., a corporation of Pennsylvania

Original application June 11, 1931, Serial No. 543,507. Divided and this application June 2, 1933, Serial No. 673,994

6 Claims. (Cl. 250—27.5)

My invention relates to electric discharge devices and has particular relation to photo-sensitive devices.

This application is a division of my application Serial No. 543,507, filed June 11, 1931 and assigned to the Westinghouse Electric and Manufacturing Company.

It is an object of my invention to provide a photo-sensitive device the character of the response of which shall be dependent on the orientation of the region of the cathode thereof that is excited.

Another object of my invention is to provide a photo-sensitive device of the type wherein the response when one region of the cathode is under excitation shall be different from the response when another region of the cathode is under excitation.

A further object of my invention is to provide a photo-sensitive device of the type wherein the response shall be dependent in a predetermined predictable manner on the relative orientation of the region of the cathode that is under excitation.

Still another object of my invention is to provide a photo-sensitive device that shall be capable of responding in a predetermined manner to localized excitation and that shall indicate the relative locality of the excitation.

More specifically stated it is an object of my invention to provide a photo-sensitive device that shall be capable of energizing a group of elements responsive thereto and arranged in a predetermined manner in accordance with the localization of the excitation of the cathode thereof.

A photo-sensitive device constructed in accordance with the practice of my invention comprises preferably a photo-sensitive cathode or a plurality of photo-sensitive cathodes disposed in a suitably evacuated container and a plurality of collecting electrodes or anodes associated with the cathode or cathodes. When a plurality of cathodes are utilized an anode is associated with each cathode and the cathodes are so constructed geometrically that the electron flow when any cathode is excited will be substantially entirely to the corresponding anode. When a single cathode is utilized it is subdivided into distinct regions and an anode is associated with each region. Each region of the cathode is of such structure that when the excitation is localized therein the flow of current is substantially to the corresponding anode.

The novel features that I consider characteristic of my invention are set forth with particularity in the appended claims. The invention itself, however, both as to its organization and its method of operation, together with additional objects and advantages thereof will best be

understood from the following description of a specific embodiment, when read in connection with the accompanying drawing, in which:

Figure 1 is a schematic view showing a photo-acoustic reproducing system incorporating a photo-sensitive device constructed in accordance with the practice of my invention;

Fig. 2 is a diagrammatic view showing a photo-sensitive device having a single cathode constructed in accordance with my invention, and

Figs. 3, 4, 5 and 6 are diagrammatic views showing several modifications of my invention.

In Fig. 1 a photo-acoustic reproducing system in which a photo-sensitive device constructed according to my invention is incorporated is shown. This system is shown to illustrate the utility of my invention.

The system shown in Fig. 1 comprises a light source 63, a condensing lens 67, whereby the radiations from the source 63 are gathered and focused on a slot 69, and a lens system 71 whereby the slot 69 is imaged on the film 25 in the form of an attenuated rectangle 73 extending across the film 25.

The film 25 is of the type provided in accordance with the parent application of which this application is a division. It does not essentially concern the present invention and need not therefore be described in detail here. Briefly, it may be said that a record 27 is impressed on the film in such manner that its orientation corresponds to the orientation in a particular set of the sound emitter corresponding to the record. In reproducing advantage can only be taken of the structure of the record 27 if a reproducing system can be provided which is responsive to the relative orientation of the record on the film 25. Such a reproducing system is incorporated in the apparatus shown in Fig. 1 and one of the essential elements of the system is the photo-sensitive device 75.

The photo-sensitive device 75, comprising an elongated container 77 having disposed therein, a plurality of independent cathodes 79 and anodes 81, is located behind the film 25. The light transmitted through the film 25 and modified by the sound track 27 impressed thereon impinges on the cathodes 79 of the photo-sensitive device 75. The cathodes 79 are energized in accordance with their disposition in the photo-sensitive device, and their state of excitation is dependent on the lateral orientation of the sound track on the film.

The cathodes 79 of the photo-sensitive device 75 are cylindrical in structure and when a particular cathode is excited the electronic current produced thereby is directed towards the corresponding anode 81. The current produced between each cathode 79 and its corresponding anode 81 is fed into a plurality of independent

amplifiers 83, 85 and 87, which, in turn, feed into a plurality of loud speakers 89, 91 and 93. The loud speakers 89, 91 and 93 are arranged in the vicinity of the picture screen (not shown) in a 5 manner corresponding to the microphones in the recording setting, and it is seen that the magnitude of the sound reproduced by the loud speakers will be dependent on the state of excitation of the individual cathodes 79 and, therefore, on the 10 original disposition of the sound-emitting bodies in the recording setting.

In Fig. 2, a photo-sensitive device 95 of a type having a common cathode 97, a plurality of principal anodes 99 and a plurality of auxiliary anodes 101 is shown. The cathode 97 and the principal anodes 99 are respectively connected to the terminals of a plurality of inductors 103 which are the input elements to a plurality of amplifiers.

It is apparent that the anode associated with the region of the cathode wherein the radiant energy is localized will receive a greater charge than the anodes associated with the other regions of the cathode. Moreover, it is a well known fact 20 that photo-electrons are emitted from the surface, in general, in a direction perpendicular to the surface. Consequently, since the cathode surface comprises a plurality of cylindrical arcs 105 and the anodes 99 are disposed at the centers of curvature of the arcs, the result produced by radiant energy of a localized character will correspond with comparative accuracy to the localization of the energy.

The auxiliary anodes 101 are disposed between 35 the principal anodes 99. The anodes 101 are connected to the mid taps 107 of the resistors 109 which, in turn, are connected to the lower terminals of the inductors 103. The auxiliary anodes 101 aid in smoothing out the characteristic 40 response of the system and eliminate any abrupt effects that may arise by reason of the sudden transfer of the reproduction from one loud speaker to another. The photo-tube 95 of the type illustrated in Fig. 2 is particularly adapted 45 to be utilized in apparatus of a type wherein the loud speakers in the central region of the reproducing stage are capable of delivering more power output than the speakers in the terminal regions of the stage.

In Fig. 3, a photo-sensitive device 107 having 50 a plurality of individual cathodes 109 and a plurality of principal and auxiliary anodes 111 and 113 associated with each cathode is shown. The purpose of the auxiliary anodes 113 in the photo-sensitive device 107 of the type illustrated in Fig. 3 is the same as the purpose of the corresponding anodes 101 in the device 95 of the type illustrated in Fig. 2.

In Fig. 4, a photo-sensitive device 115, comprising a single cathode 117 having plural-arc configuration and an anode 119 associated with each arc, is shown.

In Fig. 5, a photo-sensitive device 121, of a type having a plane cathode 123 and a plurality 65 of associated anodes 125, is illustrated. It is seen that by reason of the fact that electrons are emitted from the surface of the cathode 123 in a normal direction, the anode 125 nearest a point of excitation of the cathode 123 will receive the 70 preponderance of the electronic current from the cathode.

In Fig. 6, a photo-sensitive device 127, incorporating a cathode 129 of the type having the configuration of an arc made up of a plurality

of reentrant smaller arcs 131 is shown. A plurality of anodes 133 are associated with the smaller arcs 131.

It should be noted that, while modifications of photo-tubes having independent anodes and a common cathode are illustrated and described hereinabove, my invention may be equally as well practiced with photo-tubes having a common anode and a plurality of independent cathodes. In such a case the anode may be connected to a common terminal such as the terminal of the circuit shown in Fig. 2 to which the cathode 97 is connected while cathodes having the cylindrical configuration of the cathodes 109 of the photo-sensitive device 107 shown in Fig. 3 and 15 electrically independent of each other may be connected to the terminals of the circuit shown in Fig. 2 to which the anodes 99 are connected.

Although I have shown and described certain specific embodiments of my invention, I am fully 20 aware that many modifications thereof are possible. My invention, therefore, is not to be restricted except insofar as is necessitated by the prior art and by the spirit of the appended claims.

I claim as my invention:

1. An article of manufacture comprising a container having a photo-sensitive element disposed therein, said element being formed into a plurality of arcs of circular cylinders, and a plurality 30 of charge-collectors disposed at the centers of curvatures of said arcs.

2. An article of manufacture comprising a container having a photo-sensitive element disposed therein, said element being formed into a plurality of arcs of circular cylinders, a plurality of charge-collectors disposed at the centers of curvatures of said arcs and a plurality of charge collecting elements disposed between said arcs.

3. An article of manufacture comprising a container having a photo-sensitive element disposed therein, said element being formed into a plurality of curved surfaces, and a plurality of charge-collectors disposed at the centers of curvatures of said curved surfaces.

4. An article of manufacture comprising a container, a row of curved photo-sensitive surfaces disposed within said container, a plurality of independent charge-collecting elements, one of said elements being disposed opposite each of said surfaces, for collecting the charges emitted by said surfaces, a plurality of auxiliary charge-collecting elements disposed between said surfaces and terminals connected to said surfaces and said charge-collecting elements.

5. An article of manufacture comprising a vacuum tight container, a plurality of curved photo-sensitive surfaces disposed within said container, a plurality of independent means for collecting the charges emitted by said surfaces, said independent means and said curved photo-sensitive surfaces being disposed in groups and independent outlet connections from each of said groups.

6. An article of manufacture comprising a vacuum tight container, a plurality of curved photo-sensitive surfaces disposed in a row within said container, a plurality of independent means for collecting the charges emitted by said surfaces, at least one of said independent means being associated with each of said curved photo-sensitive surfaces and forming a group therewith and independent outlet connections from each of said groups.

WILLIAM MAURICE PATTERSON.
